UNITED STATES PATENT OFFICE.

SEBASTIAN CRUSET, OF NEW YORK, N. Y.

VISIOPHOTOGRAPH.

1,160,096.

Specification of Letters Patent.

Patented Nov. 9, 1915.

Application filed December 15, 1913. Serial No. 803,769.

To all whom it may concern:

Be it known that I, SEBASTIAN CRUSET, a subject of the Kingdom of Spain, residing at New York, in the county of New York and State of New York, have invented new and useful Visiographs, of which the following is a specification.

The present invention, which I have termed a "visiograph", is an optical instrument which is intended for use by artists, surveyors and others. Generally speaking, this instrument is designed to be supported before the eyes, either by being worn like a pair of spectacles or by being mounted on a suitable structure, so that the view, scene or object to be sketched or accurately delineated, can be seen as if divided into squares or other sections which can be reproduced section by section on a paper or canvas that is ruled in sections or fractional areas corresponding to those into which the view, scene or object is divided by the visiograph.

In its simplest form, the visiograph consists of means in front of each eye for roughly dividing the view into sections to enable the ascertainment of the relative positions and sizes of objects that go to make up the view, but in its more developed form the visiograph is based on a new scientific principle of vision and of perspective.

A few general observations will be expedient to better appreciate the purposes of the visiograph. As a simple illustration, if a group of scattered spherical objects are drawn according to the former principles of perspective, all the objects will be represented as spheroidal, being greater horizontally than vertically, except in the case of that ball which might be directly in front and at the point of the axis rays, which of course, would be truly circular, and those more remote from the axis rays would be more spheroidal. Furthermore, objects having straight vertical and horizontal lines will according to the former method of perspective, be shown in the drawing as straight and geometrically parallel. All of this is contrary to the principle of sphericity of the space and of the vision.

According to my discoveries and with the aid of the visiograph, it is possible to sketch objects perspectively in their true proportions and relations. If a transparent flat plate be placed before the eyes and the outlines of objects seen through it be traced on the plate, it will be found that all vertical

lines bend up from the horizon gradually toward the zenith, and from the horizon gradually down toward the nadir; and all horizontal lines will also gradually bend toward two vanishing points in the horizon situated to the right and left of the observer and 180 degrees apart. This bending of the lines demonstrates that the sphericity of vision is a fact as can be proven with the visiograph.

To ideally sketch or represent a scene in conformity with the vision effected inside the eyes, the artist should be stationed within a large hollow transparent or crystal sphere with his center of vision at the center of the sphere from which he could cast his sight in all directions; and this sphere like a miniature of the celestial sphere should be divided in equal spaces of degrees by great circles running through its poles, or from the zenith through the horizon or equator to the nadir; and by small circles running parallel with the horizon, whereby numerous small areas of spherical squares are formed, which may be subdivided by diagonal lines into smaller areas. The scene that is observed through the sphere will be divided by these circles into small sections, which can be exactly reproduced on paper that is correspondingly ruled or divided. By this method all horizontal and vertical lines will have their proper values, and spherical objects, as in the example above given, will be represented by true circles, no matter where they appear to be located, as each will be viewed in its turn by the direct ray of the sight which in the sphericity of vision is shifted at will, and in a pivotal swing or radius-spherical movement to every part of the spherical space.

It is one of the objects of the present invention to approximate as nearly as possible and in a thoroughly practical manner this ideal sectionalized transparent sphere, by making the visiograph which provides for the eyes transparent or open visual fields that are divided by longitudinal and latitudinal and other lines, so that bodies can be seen through these lines and be represented exactly as they appear; and by providing the necessary fields, means for sighting and focusing, and reflecting devices spherical views, semi-spherical cartographic views and panoramic views, as well as partial views, can be easily and accurately made. Furthermore by the adoption of suitable fields

the visiograph possesses additional advantages in that optical measurements and tests can be reliably and effectively performed.

For a more complete understanding of the invention reference is to be had to the accompanying drawings, taken in connection with the following description and appended claims.

In the accompanying drawings, which illustrate several embodiments of the invention and wherein similar reference characters are used to designate corresponding parts through the several views: Figure 1 is a front view of the simplest form of the instrument or sketching visiograph. Figs. 2 and 3 are respectively plan and side view thereof. Fig. 4 is a plan view of the instrument folded. Fig. 5 is an edge view of the folded instrument. Fig. 6 is a plan view of the panoramic visiograph. Fig. 7 is a perspective view thereof showing the manner in which the visiograph is applied to the head of the user. Fig. 8 is a plan view of the surveyor's or spheric visiograph. Fig. 9 is a side view thereof. Fig. 10 is a fragmentary perspective view of that portion of the left horizontal quadrant that lies in front of the left eye, showing the mirrors thereon, the quadrant adjusting device and focusing means, etc. Fig. 11 is a detail perspective of the left side of Fig. 10, parts being broken away. Fig. 12 is a bottom plan view showing the details of the portion of the horizontal quadrant immediately in front of the eye. Fig. 13 is a rear view of the spectacle-like brackets to which the horizontal quadrants are connected. Fig. 14 is a front view of one of the main or horizontal visual fields and its supporting frame, the field being of that type usable for making panoramic views. Fig. 15 is a front view of one of the visual fields for use in making partial views. Fig. 16 is a plan view of one of the field frames. Fig. 17 is a perspective view of one end of the field frame showing the field clamping or fastening member. Fig. 18 is a view of the opposite end of the field frame. Fig. 19 is a rear view of the surveyor's or spheric visiograph as seen from station points A², A³, shown in Fig. 8. Fig. 20 is a front view of the extension sections of the vertical visual fields. Fig. 21 is a perspective view of one of the vertical visual fields and its frame. Fig. 21 is a reverse perspective view of the same. Fig. 22 is a disassembled view of one of the double sight preventing screens and sighting mirrors on the upper side of each horizontal quadrant in the type of visiograph shown in Figs. 6 and 7. Fig. 22^a is a view of the mirror detached. Fig. 22^b is a perspective view of the parts in Fig. 22 assembled. Fig. 23 is a perspective view showing the parts in Fig. 22 assembled on the quadrant and also showing the lower screen. Fig. 24 is a dia-

grammatic view in plan of the three mirrors on each horizontal quadrant in spheric type of visiograph, Fig. 8, and showing the manner of using the horizontal mirrors for to ascertain a lateral point in the horizon 70 degrees of the axis ray of sight. Fig. 25 is a diagrammatic side view of the same mirrors showing the manner of ascertaining a point 45 degrees above the horizon or axis ray of sight. Fig. 26 is a diagrammatic side 75 view of the mirrors on the lower end of each vertical quadrant, showing the manner of ascertaining a point 45 degrees below the horizon or axis ray of sight. Fig. 27 is a disassembled view of the mirrors on the lower end of each vertical quadrant. Fig. 28 is a side view of the pivotal movement structure whereby the visiograph is universally moved carried and supported independently of the artist or surveyor. Fig. 29 is a plan view of the same on a reduced scale. Fig. 30 is a sectional view on line 30—30 Fig. 29. Fig. 31 is a fragmentary perspective view of uppermost portion of the visiograph pivotal movement structure. Fig. 32 is a detail perspective of the means (with its parts separated) for connecting central portions of the visiograph with the structure for the pivotal movement. Fig. 33 is a detail perspective view of one of the means 90 for connecting the sides of the visiograph with the support. Fig. 34 illustrates a partial view, taken with the aid of the visiograph, the view being drawn on paper divided by lines in correspondence with the 100 lines on the visual field through which the view was seen; this being an example of a spherical perspective projection upon its plane of delineation. Fig. 35 illustrates a panoramic view representing half the horizon, made with the visiograph shown in 105 Figs. 6 and 7 and is another example of a spherical perspective projection with its plane of delineation. Fig. 36 illustrates half of a semi-spherical terrestrial survey made 110 with the aid of the visiograph shown in Figs. 8, 9, 19 and 20, and it illustrates also an example of a visio-spherical projection drawn upon its plane of delineation. Fig. 37 illustrates a semi-spherical terrestrial and celestial survey and illustrates also another example of a visio-spherical projection with its plane of delineation. 115

Referring to Figs. 1 to 5 inclusive (which show the form of visiograph intended for 120 use by advanced artists and surveyors who, in sketching, need but few guiding lines, measurements and points) it will be observed that the instrument is so designed as to be specially adapted for out-door use, 125 without the winds, rain or snow causing annoyance, since the instrument is light and simple in construction, and is fieldless and free from many of the other devices essential in the more complicated forms of the 130

instrument that are used for panoramic, cartographic and spheric views. This sketching visiograph, which is preferably, although not necessarily made of aluminum, comprises a pair of symmetrical plate-like members D and D' or half quadrants so to speak, which are adapted to be held respectively in front of the right and left eyes and edgewise thereto in a horizontal plane so that both plates or quadrant sections will appear as a line corresponding to the horizon or to a line parallel therewith. These plates D and D' are provided with suitable means for enabling the ascertainment of the relative positions and dimensions of objects or component parts of a view or scene to be sketched. In the present instance, each plate has at its outer edge a degree scale consisting of upwardly projecting lugs C struck out of the metal and spaced 5 degrees apart in a line concentric with the center of vision A and A' of the eyes. The zero ends of the scales C and C' are spaced apart a distance corresponding to the distance between the centers of the two eyes or stations A and A'. Between the scales and the eyes, the plates D and D' have sighting devices 1 and 2 disposed in line with the zero and 35 degree lugs or divisions of the scales, the purpose being that when the lugs 1 and 2 appear to the vision directly coincident with the zero and 35 degrees divisions, the instrument is properly set or focused with respect to the user's eyes. The instrument is designed to be worn spectacle fashion, and consequently the inner portions of the quadrant sections D and D' are provided with nose rests L which bear on the bridge of the nose and hingedly connected with the rear corners of the sections D and D'. The sections D and D' are ear engaging members M and M', which extend rearwardly over and rest on the ears, there being tapes or equivalent means 3 fastened to the ear engaging members so as to extend back of the head and connect together for firmly retaining the device on the head. The scales C and C' are used for horizontal measurements, and for vertical measurements perpendicular scales Z and Z' either straight or arcuate are employed. These are located at the forward edge of the quadrant D D' and centrally between the scales C and C', one extending upwardly and the other downwardly so that they can be seen above and below the horizon. They are thin bar like members having horizontal degree division lugs or projections 4 that can be easily seen. To prevent double sight only as to the horizontal scales C and C' the quadrant sections have screens N and N' so placed as to be close to the eyes without intercepting the view of the scales C C' each by the proper eye. To enable the instrument to be more conveniently carried it is foldable to about half its normal size. Hence the quad-

rant sections D and D' are connected together with hinges d and d' and the pintle 5 of the hinge d forms a pivot for the scale elements Z and Z' whereby they are hingedly connected with the parts D and D' and can fold to a position parallel with them as shown in Fig. 4. The parts D and D' are normally held open or locked in a common plane by a bolt J that is slidably mounted on the part D' and movable in a guide j and extends into a pocket or keeper j' on the part D. When this bolt or slide J, Fig. 2, is moved to the right, the parts D and D' can be folded together as shown in Figs. 4 and 5.

In sketching, an artist ordinarily begins by selecting the prominent points or features of the scene or view to be sketched and in ascertaining their relative positions, dimensions, etc., lays them out on the paper or canvas. In doing this it is usual to employ the pencil or brush, holding it in front of the eyes to get the different heights and level of objects and their relative sizes and positions. This method is unreliable and lengthy as much time is required on taking the pencil or brush from the work to the eye and back again. These disadvantages are entirely overcome by this sketching visiograph and by its use a scene or view can be quickly and with fair accuracy laid out on the paper or canvas. With the visiograph in position the height and level of objects and their relative sizes and positions can be easily and reliably ascertained by means of the horizontal and vertical scales, and as the plates or quadrant sections are on a level with the pupil of the eyes, they do not interfere with the eyes seeing the drawing paper or the canvas which the artist may hold in his lap, hand, or on an easel. He need not change the position of his head in shifting his gaze from the scene to the paper to draw thereon and vice versa, as only the eyes move, but any time he wants to locate one point with respect to another point, if horizontally, he only has to move the head a little bit to bring the edge of the quadrant to that point to have a horizontally guide; if vertically he disposes of the vertical bar of-scales which he can bring instantly to any place desired.

In beginning with the visiograph a certain point in the horizon is selected as the center of vision, the term center of vision meaning the point where the two rays of the eyes meet, and consequently these two rays constitute the axis rays of the sight that pass straight and through zero of the two scales C and C' of the visiograph. The whole scene may be considered as divided horizontally by the horizontal edge of the quadrant, and vertically by the scale of divisions Z Z'. Because of double sight the vertical scales appear to the vision as being

in pair, about 14 degrees to each side of the middle of the visiograph. It is therefore easy to imagine lines running horizontally through corresponding divisions of the vertical scales, and lines running vertically, or parallel to the vertical scales, through the divisions of horizontal scales, so that in effect the scene may be divided into square sections. It will be understood that the paper or canvas on which the scene is to be sketched will be divided in square sections as a plane of delineation to correspond and hence the scene can be observed piece by piece or section by section and reproduced on the paper in the same manner.

Taking up the panoramic visiograph reference is to be had to Figs. 6, 7, 10 to 18, 22 and 23. Although for convenience this type of instrument shall be termed a panoramic visiograph, it is to be understood that it can be used for indoor sketching and copying, or outdoor sketching, or for making perspective or partial views. It is worn on the head like the simpler form of visiograph. It embodies two geometrical horizontal quadrants D^2 and D^3 disposed in front of right and left eyes respectively. The quadrants, which may be flat plate-like members, perform the function primarily of supports for the visual fields, focusing, sighting and other necessary devices. The quadrants are suitably fastened to spectacle-like brackets L^2 and L^3 which fit over the eye cavities and have openings 6 for the use of the sight, the lower edge of the brackets being shaped to comfortably rest on the bridge of the nose. The openings 6 may obviously be provided with spectacle lenses for those persons who need glasses. The brackets extend rearwardly under the temples and have hingedly connected with their rear ends at 7, ear engaging members M^2 and M^3 respectively. A wire or equivalent means K. extends behind the head from one ear engaging member to the other, the forward ends of the wire extending along the members M^2 and M^3 to the rear portions of the quadrants where the ends of the wire are connected with clamping bolts P that are adjustable in slots 9 in the quadrants, whereby wire can be adjusted to suit heads of different sizes; the rear ends of the ear engaging members are provided with series of notches E' with which the wire K is engaged. The wire K is made in two parts having overlapping slotted ends 10 and 10' at the middle, which are adjustably connected by a clamping bolt Q. By loosening this bolt the ends 10 and 10' can be slipped inwardly or outwardly to narrow or widen the head embracing means to comfortably fit the shape and size of the user's head.

The eye balls are designated by the letters A^2 and A^3 and the axis rays of sight are represented by the dotted lines B^2 and B^3 .

The quadrants D^2 and D^3 have focusing devices 11 and 12 in the form of upstanding lugs or projections which will coincide with the axis rays B^2 and B^3 when the instrument is properly focused for the sight. All persons do not have their eyes set the same distance apart, so that it is necessary to laterally adjust the quadrants toward or from each other until the devices 11 and 12 of the respective quadrants coincide with the axis rays of sight B^2 and B^3 as shown in Fig. 6. This adjustment is affected by two right and left hand screws G and G' that lie between the quadrants and have threaded engagement with nuts g and g' fastened to the quadrants. By turning the screws in one direction the quadrants move apart and by turning in the opposite direction the quadrants move together. After adjustment, the quadrants are clamped against movement by two pairs of clamping links J and J' pivoted respectively at 13^a and 13^b to the quadrants D^2 and D^3 , said links being arranged in over-lapping relation and formed link-like to provide a large area of frictional contact and through them pass a clamping bolt 14. To facilitate the proper positioning of the instrument on the head, the quadrants are respectively provided with near scales of sighting lugs 15 and 15^a which are adapted to coincide with far scales of sighting lugs 16 and 16^a.

The visual fields C^2 and C^3 are disposed at the forward edges of and stand perpendicular to the quadrants D^2 and D^3 respectively, with portions extending below and above the same. These fields, which are preferably made of celluloid sheet or any other transparent medium with divisions or guiding lines thereon, are removably fastened in the frames H and H'. These frames are alike, as are also the any two companion visual fields, but different sets of fields may be used according to the nature of the work to be performed. Each field frame, as shown in Figs. 16 to 18, comprises upper and lower horizontal bars h and h' and end vertical bars S and S', the bars being so arranged as to form a stiff rectangular frame. The front edges 17 of the bars h and h' are curved on an arc concentric with the center of the sight in the eyes and the visual field celluloid sheet will bear against their curved edges and partake of the curvature thereof. The end bar S' is rigidly fastened to the top and bottom bars h and h' but the bar S is movably fastened for the purpose of removably locking the field on the frame. The bar S has upper and lower lateral arms T and T' which are respectively connected by pivots t and t' with the bars h and h', and on the latter are seats 18 into which the extremities of the bar S engages when it is in the field holding position. Swinging loops or clips

U' and U² are mounted on the upper and lower ends of the bar S to engage over the extremities of the bars h and h' for locking the bar S in its seat 18. Headed studs or buttons 19 and 20 are provided on the bars S and S' and in the ends of the celluloid fields are button holes 21 and 22 which receive the buttons, as clearly shown in Fig. 14. When the movably locking bar S of 5 the field frame is in locking position the buttons are in the narrow portions of the button holes, thus rendering detachment of the transparent fields impossible. The upper and lower bars h and h' may be provided with pins 23 that fit in aperture 24 of the fields. The field frames are detachably secured to their respective quadrant by hooks I and I' that embrace the center bars S and S' which have spaced collars or 10 shoulders 25 between which the bills 26 of each hook engages. Each hook comprises a pair of members i and i' disposed on the top and bottom surface of the quadrant and connected therewith by a pivot i² and in the 15 quadrant in concentric relation to the pivot is a slot 27 to receive a clamping bolt 28 that extends through parts i and i' of the hooks and clamp them frictionally against the quadrant. By loosening the bolt the 20 hooks can be unhooked from the center of the field frame. Clips, loops or other suitable devices U are arranged on the end bars of the field frame to engage over the bills 26 as shown in Fig. 7 so that said bills 25 cannot become detached from the field frame.

The fields C² and C³, which are always in companion sets or pairs, divided by vertical or latitudinal and horizontal or longitudinal 25 lines l and l' into squares each equivalent to an area of 25 degrees according to the field shown in Fig. 14, or 100 degrees according to the field shown in Fig. 15. Diagonal lines 12 divide the squares into smaller sections 30 for facilitating the sketches of objects, etc., seen through the field. In Fig. 14 the field C³ has a total observation area which is 45 degrees wide and 50 degrees high. The field C² in Fig. 15, which is the right field of another set, is 46 $\frac{1}{2}$ degrees wide and 50 degrees high and makes with its mate a field of 35 convenient size, but the areas of the field may be varied if desired. Fields of the kind appearing in Fig. 14 are suitable for 40 making a type of panoramic views like the one represented in Fig. 35 where all the horizontal and all the vertical lines are drawn geometrically parallel, the former ones corresponding to the planes of circles concentric to a common axle with the horizon; and the latter ones corresponding to all the plumb lines and azimuths, while the fields divided as in Fig. 15 are used for making partial views, of the nature shown in 45 Fig. 34, that may be termed perspective

style, as the view is seen through squares laid out on the principle of spherical perspective, in that the supposed horizontal lines l' are not geometrically parallel nor straight but perspectively parallel and bend gradually to converge to vanishing points that lie in the horizon 90 degrees to the right and left of the observer. The vertical lines l drawn geometrically parallel and straight are seen in perspective when looked 70 in the visiograph, they follow their path similar to that of the horizontals, bending gradually toward their vanishing points 180 degrees apart, the zenith and the nadir. The diagonal lines l² bend also to correspond 80 and to divide the field of perspective squares in front of the eyes.

The innermost vertical lines of the fields will always coincide with axial rays B² and B³ and when the quadrants are properly focused and the sight of both eyes is directed straight ahead to a distant point the inner vertical lines of the fields C² and C³ will 85 meet or overlap and the two fields thus connected appear like one field covering a range 90 of vision of space equal to 90 degrees of the horizon and to 50 degrees meridionally. This belt of space is seen through the fields as divided into sections by reason of the lines on the fields, and by using paper or a plane 95 of delineation ruled the same as the fields, portions of the view or scene observed in the individual sections of the field can be reproduced in the corresponding sections of the ruled sketching paper, so that great accuracy 100 as well as facility and despatch is possible.

It is important that means be provided for preventing confusion resulting from double sight. For this purpose upper and lower 105 screens N² and N⁴ are engaged on the quadrant D² and upper and lower screens N³ and N⁵ are arranged on the quadrant D³. These screens are disposed between the axis rays of 110 vision so that the visual field will not be obscured, and each screen is made of a base part n, fastened to the quadrants and a tip part n' connected by a hinge n² so that the screens can be folded and take up less space 115 when the visiograph is to be packed in its carrying case. The tip members of the lower screens will normally hang in proper 120 positions for use but the upper tip members are provided with means of locking them upright, as shown in Figs. 22 and 23, the upper tip members, each has a lug 30 behind the upper member n' and a catch 31 pivoted on the upper member n' is thrown down to locking position behind the base member and prevents the tip member from dropping. 125 By throwing the catch 31 up above the hinge, the tip member can be swung down.

In making panoramic views the first step to take, especially in views embracing 360 degrees of horizon, is to ascertain the four 130

- cardinal or diametral points on the horizon. This is accomplished by an arrangement of mirrors and sighting devices on the quadrants as shown in Figs. 6 and 7 and in Fig. 24. The two mirrors FF' in front of the eyes A² A³ reflect line EE' perpendicularly to the axis rays A² B² and A³ B³ which make together the visual central ray of vision that strikes a point in the horizon, and line EE' strikes the horizon upon two opposite points or extremities of its diameter, thus obtaining a semicircle; the adjacent semicircle is connected by focusing the visiograph to this side of semicircle which diameter and extremities are the same ones found and to be refound with line EE' and now the perpendicular axis rays A² B² and A³ B³ give the forth point on the horizon.
- The drawing out of a panoramic view is a very simple operation to perform. The sight is capable of embracing and sketching easily 30 degrees longitudinally on each side, right and left, but, because vertical lines aside of the center of vision bend gradually toward vanishing points, it is absolutely necessary in panoramic views, to make use of a rotation movement, that is done simply by shifting the center of vision from 5 to 5 or 10 to 10 degrees every time the work of such sectional space is ended along the vertical range of squares; by so doing the vertical line which crosses the center of vision coincides with all the plumb lines of the view.
- The mirrors and sighting devices referred to will now be described. The mirrors F and F' are arranged adjacent and between the eyes, respectively at acute angles and capable of turning in and out; and to be kept fixed when the sighting devices or lugs E and E' extending upwardly from the lateral portions of the quadrants D² and D³ are reflected to the eyes. The mirrors are mounted on the lower or base members n of the upper screens, there being, as shown in Figs. 22 and 22^a, an opening 32 in each base member to receive lugs 33 on the back of each mirror frame, which lugs are bent after being inserted in the opening 32 so as to be retained. The bottom of the mirror has a flange 34 with a hole 35 through which passes a screw or clamping device 36 that adjustably fastens the screen and mirror to the quadrant. When the mirrors are properly set and it is designed to locate a point 90 degrees to the right, the right eye is used to look into the right mirror to see on what point on the horizon the sighting devices E' strike, the mirror showing a sufficiently large area of the horizon to enable the point to be readily distinguished, by its relation to surrounding objects seen in the mirror, when the user shifts his position to face the point sighted. In ascertaining a point 90 degrees to the left, the left eye, left mirrors

and left sighting devices are used as will be obvious.

The pair of quadrants D² D³ Figs. 6 and 7 are open from the axis rays A² B² A³ B³ to 45 degrees respectively, but the parts of the quadrant at the side of the opening therein, are fastened together at all times when the instrument is not in use, by bracing members O and O' which are thin plates so mounted as to be presented edgewise to the eyes in substantially the same plane with the quadrants. These members O and O' are connected by hinges 37 (Fig. 12) with the underside of the quadrants D² and D³ respectively and they may be left open to allow a clear view of the fields in which case they hang down out of the range of vision, as shown in the left quadrant of Fig. 6 and right quadrant of Fig. 8 and in Fig. 10. The free end 38 of each bracing members is adapted to be engaged by and held in closed position by a sliding bolt 39 Figs. 11 and 12, on the under side of each quadrant, the bolt being movable in a guide 40. On the top surface of each gate are radial lines 41 centering to the adjacent eye and arranged 10 degrees apart. These lines are here for two purposes, first; their presence marks the continuation of the interrupted quadrant, second; they may be used in setting the instrument, by placing it slightly below the pupil of the eyes, whereby their radial direction can be seen to ascertain whether or not they converge directly to their corresponding pupils. If not, the instrument is shifted slightly to the right or left until the lines are seen to converge straight to the pupils, in which case they must register also with the vertical lines of same degrees on the fields. The instrument is now raised to the level of the pupils of the eyes and the quadrants are seen as horizontal line, and in this position the instrument is fastened to the head. The members O and O' can now be opened so as not to obstruct the view of the fields. As the visiograph is made of light metal it must be stiffened at certain places. Hence underneath the parts of each quadrant are fastened ribs V and V' which are arranged and formed as shown in Figs. 11 and 12. The bracing members O and O' are used primarily to give added rigidity to the structure.

Considering now the third type of visiograph, the one used for making semi-spherical cartographic and semi-spherical views, it will be observed from Figs. 8, 9, and 19 that it is the same as the so called panoramic visiograph in Figs. 6 and 7, except that certain additions are made thereto. The additions are briefly the vertical quadrants D⁴ and D⁵ vertical fields C⁴ and C⁵ and their frames H⁴ and H⁵, sets of upper mirrors and sets of lower mirrors, whereby

points out of the range of vision can be located for use in refocusing the instrument to different parts of the space including the points of the zenith and the nadir. The 5 horizontal fields C^2 and C^3 are only 20 degrees in vertical dimension, and 90 degrees in length and concentric to the eyes horizontally. The vertical quadrants D^4 and D^5 are disposed edgewise and concentric to the 10 eyes in two vertical planes and parallel to each other. To support these vertical quadrants on the horizontal quadrants D^2 and D^3 , the inner edges of the latter near the front corners are each formed with two vertical 15 plates X , the upper plate 42 has slots 43 and in the lower plate horizontal lugs 44 as shown in Figs. 11 and 19. Each vertical quadrant is placed flat against their respective plates X , the lugs 44 entering openings 20 45 in the quadrants and U -shaped fastenings or clamp Y hold the parts adjustably together. Each clamp is a U shaped structure having a head 46 , Figs. 11 and 19, which bears on the vertical quadrant and has two 25 threaded shanks 47 that pass through slots 48 in the quadrant and enter the slots 43 in the plate 42 . In Fig. 19 only one threaded shank 47 , which has a milled nut 49 thereon, can be seen on each side, as the other one is 30 behind it, and in Fig. 9 the slots 48 are seen as arcuate, and enable the quadrants to be moved down 15 degrees. The vertical quadrants are connected together and relatively adjustable by right and left hand screws G^2 35 and G^3 Figs. 8, 9 and 19. Their use is for focusing the vertical fields when the visiograph is engaged to sketch bodies close to the station point.

Field frames H^2 and H^3 which are symmetrical, are mounted on the quadrants D^2 and D^3 . Each frame is constructed as shown in Fig. 21; that is to say, it is approximately rectangular in front view and curved in side view on the same arc of the 45 quadrant to which it is fastened. Lugs 50 , which have slots 51 , extend rearwardly from the frames and clamp bolts 52 in the quadrant pass through this slot 51 and removably secure the frames to the quadrants, as 50 the frames must be removed and mounted during certain stages in making a semi-spherical view as will be hereinafter explained. On each frame is adapted to be fastened a field. The fields C^4 and C^5 , 55 which are each 75 degrees in vertical length and 10 degrees horizontally in width, are ruled or divided into spherical squares or sections and are suitable for sketching a view extending from 30 degrees above the 60 horizon to 45 degrees below and 20 degrees (the combined width of the two fields). As the views to be drawn are to represent the sphericity of the space all the lines of these fields are projected lines, representing to the 65 eye's sight the concavity of spherical de-

grees; for this reason the vertical lines that have to coincide with the vertical circles of the celestial sphere, converge and bent above and below the horizon in such a manner as to go to their meeting points—the zenith and 70 nadir, while the horizontal lines are bent concentric and parallel to coincide with the almucantars of same sphere.

As the range of vision vertically is limited, by reason of the brows and cheeks, the 75 fields C^4 and C^5 have their limits at 30 degrees above the horizon. In making a celestial spherical cartograph, it is necessary to sketch first from the horizon to a height of 80 30 degrees by means of the fields in the position shown in Fig. 19. Then the fields are inverted, so that the formerly lower ends of the fields can be used to sketch from the 30 degrees level to the height of 45 degrees. But in order to see the 45 degrees up in the 85 sky, the vertical quadrant must be lowered 15 degrees and the axis rays of the visiograph must be pointed at 15 degrees above the horizon so that while the sight can be directed from the horizon up to 45 degrees, 90 the section or the belt from 30 degrees can be sketched. The vertical quadrants are moved down 15 degrees by loosening the nuts 49 . This arrangement will bring the 15 degrees division α on the longer ends of 95 the vertical fields to the point of the axis rays B^2 and B^3 of the horizontal quadrants. After the sketch has been completed to the 45 degree lines, the fields C^4 and C^5 are removed from the frames H^2 and H^3 and the 100 fields C^6 and C^7 , Fig. 20, are substituted for enabling the sketching to be completed from the 45 degree line to the zenith. These fields C^6 and C^7 are divided by vertical or latitudinal lines which vanish to a point that 105 corresponds to the zenith, when the instrument is properly held and the lines converge upwardly. When sketching a terrestrial cartograph, the fields C^6 and C^7 will be put on in the frames with the lines converging 110 downwardly. The fields which are of transparent material, such as celluloid, are held in position on their frames by pins 52 thereon engaging in apertures 53 in the fields and also by clamps U^3 and U^4 on each frame. 115 Each clamp has members 55 which slide through openings 56 Fig. 21^a in the field frame and have springs 57 which hold the clamp tightly against the field which has one end inserted under the clamp and between the members thereof. 120

Sighting devices E^4 and I are arranged in pairs at the upper and lower ends of the vertical quadrants D^4 and D^5 and lie in lines that converge to the eyes or stations A and 125 are disposed 45 degrees above and below the middle of the quadrants. Mirrors F^2 and F^4 are associated with sighting device on the upper end of the vertical quadrant D^4 and mirrors F^3 and F^5 with those on the 130

upper end of quadrant D⁵. The mirrors F² and F³ are disposed directly over the double left and right-preventing screens on the upper side of the horizontal quadrants and 5 said mirrors are adjustably arranged on axles, such as the screws or spindles 36 that fasten the screens to the quadrants. The mirrors F⁴ and F⁵ are mounted directly over the eyes and in front of the brows, on 10 the brackets L and L'. These mirrors are adjustable on horizontal axles 58 Fig. 8, fastened in lugs 59 on the said brackets. Coöperating with the sighting devices E⁵ 15 are mirrors F⁶ and F⁷ mounted in a frame R constructed as shown in Fig. 27 and mounted as shown in Figs. 8 and 9. Only one set of these mirrors need to be used, being adjustable to the lower part of either vertical quadrant and these are shown fastened 20 by a screw or equivalent device 61 that passes through openings 62 in the frame R and screws in the quadrant D⁴. These two mirrors F⁶ and F⁷ are fixed, the reflecting angle to be obtained with them is secured 25 when frame R is adjusted in its exact position on the vertical quadrant. Additional sighting devices E⁶ and E⁷ are arranged on the vertical quadrants at angles of 30 degrees above and below the middle of the 30 quadrants and these are used to insure the proper position of the vertical quadrants with respect to the vision.

In Fig. 24 the mirrors associated with the left eye are shown and the dotted lines 35 illustrate the use of the mirror F in obtaining a cardinal point or one 90 degrees to the side of or at right angle to the visual ray A—B.

Fig. 25 is a side view of the group of 40 mirrors shown in Fig. 24, and illustrates the use of mirrors F² and F⁴ to enable the eye to see the sighting devices E⁴ on the top of the left vertical quadrant. The lower mirrors F⁶ and F⁷ are shown in use in Fig. 26 45 to sight a point in the view 45 degrees below and from the visual ray A—B.

For panorama and spherical surveying work it will be more convenient and reliable to mechanically support the visiograph, 50 rather than wear it, as shown in Fig. 7. In sketching partial and small views the visiograph can be carried on the head with satisfactory results. A support for the visiograph in drawing larger work insures precision and stability and enables the artist to discontinue his work and resume it at any time with the visiograph remaining in the meantime in its exact position. The visiograph support is essentially a pivotal 55 movement structure and comprises a base, a plurality of legs fastened thereto, a horizontal circular track supported by the legs at about the height of the artist's eyes when he is positioned within the said structure;

a carriage or frame movably mounted on the 65 track and capable of making a complete revolution so that the visiograph, which is carried by the carriage on the track, will have a full sweep of the whole horizon or any line parallel therewith, as in making panoramic views, spherical surveys, etc., and means for mounting the visiograph on the carriage in such a manner that the sight with the visiograph can make full vertical sweeps from the horizon to the zenith and to 75 nadir, when is engaged in spherical surveys or delineations.

The base p is a ring having openings p' to receive nails, screws, staples, wires or other means p² for securely fastening the 80 base to the floor, ground or other supporting surface, and detachably secured to the upper surface of the base ring p are shoes p³ attached by screws p⁴, said shoes being fitted to the lower end of track supporting 85 legs m⁵. These legs have caps o on which rest lugs o' projecting outwardly from under the circular track a', said lugs being held fast to the legs by screws o². The legs are made in two sections, connected by 90 stretching means or screws n⁵ whereby the track a' can be leveled. The track a' is made in three sections, one section 63 being a half circle, and two sections 64 and 65, being each quarter circles, which altogether 95 make a circular track, as shown in Fig. 29, that is supported by eight legs. This complete track allows the circular or rotating movements of the visiograph to different angles in respect to space. 100

In Fig. 28 the pivotal movement structure is shown in use with only the half section of the circular track, and five legs supporting it, two legs being behind the near ones. In this condition, the visiograph, which in 105 this figure as well as in Fig. 29 is shown in dotted lines, is held to be carried in all its radius—spherical movements. The carriage or supporting frame for the visiograph consists of a horizontal semi-circular member 110 a that overlies the track and has small rollers a² which run in a groove a³ (Fig. 29) in the track and the ends of the member a are hingedly connected at a⁴ with the ends of a vertical semi-circular member d which carries a central moving and supporting means for the visiograph. The upper portion of the arched member d is steadied by an arm or quadrant between it and the middle of the base member a. This quadrant comprises scaled telescoping or slidably connected arcuate parts e and f adjustably held fixed by a set of screws h and a clamp i. The upper end e' of the part e passes through the member d (Fig. 31) and between lugs d' 115 on the latter and a screw d² passing through the lugs d' and the end e' secures the part e to the member d. Stability is given to the 120

125

visiograph holding carriage by means of an arm or quadrant bracket g , which has its bottom secured to one of the legs, and has its upper end terminated at a point adjacent to the vertical axis on which the carriage rotates, there being in the upper end of the bracket a screw t^5 which extends into a socket t^6 on the top of the member d (Fig. 31) and forms a pivot about which the carriage for the visiograph turns. The part g' which carries the pivot t^5 is hinged at g^2 to the main part of the bracket and can be moved out of the way when the tips of the vertical fields of the visiograph are fully raised to the zenith. In the upper end of the bracket g is inserted a member g^3 that carries a needle v that extends vertically and in the vertical turning axis of the carriage, and is used when pointing the sight to the zenith, in which case the semi circle or member d is moved to the right into the dotted line position Fig. 28, by shortening the quadrant f . In using the needle, the part g' is thrown upwardly out of the way, but the member g^3 is first removed to enable the part g' to swing upwardly on its hinge g^2 and the member g^3 is then put back.

The central bracket or attaching means for the visiograph consists of two arcuate pieces c and c' that extend inwardly from the arched member d and have their inner ends fastened to a slotted quadrant b which is concentric with the horizontal axis on which the member d swings. A slide and clamp l^6 is adjustable in the slot b' of the quadrant b and on this device l^6 are opposite extending hinged loops l^7 which are adapted to engage with double hooks r and r' that are attached to the right and left horizontal quadrants of the visiograph Fig. 32. Means are provided for attaching the side of the visiograph to the carriage or to some part carried thereby. Brackets g g^a constructed as shown in Fig. 33 and arranged as shown in Figs. 28 and 29, are mounted on horizontal extensions a^6 of the pintles of the hinges a^4 (see Fig. 33), such extensions extending into eyes q' of the brackets. The end q^2 of each bracket is provided with a slot q^3 into which extends a clamping screw q^4 that screws into the visiograph quadrants. A bracing member j^3 concentric with the horizontal axis or the eye q' is fastened to each bracket and through the slot j^4 of the brace j^3 passes a clamping screw j^5 that screws into a threaded socket piece j^6 on the member d , as shown in Fig. 33. When the visiograph is adjusted up and down on the horizontal axis, while the member d is stationary, the slide and clamp l^6 of the quadrant b is loosened, as are also the screws j^6 and these elements are again tightened when the desired adjustment is obtained. The device l^6 and screws j^6 are, however, not disturbed

when the position of the visiograph is adjusted by swinging the member d up and down. To prevent the visiograph holding frame or carriage from turning on the carriage after the visiograph is set ready for work, a plurality of clamps K are provided on the base circle or member a to grip the track. Each clamp comprises oppositely disposed spring jaws K^1 and K^2 fastened on the base member a and provided with a screw K^3 which when turned one way opens and releases the jaws and when turned the other way closes and grips the jaws.

In using the visiograph pivotal movement, it will be assumed that a survey of the whole visible land is to be made as in Fig. 36. The visiograph is adjusted to the position shown by dotted lines Fig. 28 and the artist positions himself behind the visiograph and in looking forward observes the scene to be sketched through the two squared bands formed respectively by the two horizontal fields and the two vertical fields intercrossing the point of the axis rays of sight. The two axis rays meet or merge at some cardinal or other selected point in the horizon, as for instance a^{10} Fig. 36, which point is seen through the fields at points c^{10} Fig. 19. The whole scene that is seen through the fields is divided into small square sections and quarters thereof by reason of the lines on the fields. The paper on which the sketch is to be made is ruled by longitudinal lines or circles a^{11} concentric with the nadir, latitudinal lines or radii a^{12} and diagonal lines a^{13} Fig. 36, this being the plane of delineation for visio-spherical projection. The lines all on the paper correspond to the lines c^{11} on the fields Fig. 19; lines a^{12} to lines c^{12} , and lines a^{13} to lines c^{13} . This net of concentric circles with their radii constitutes a projection of the celestial spheres seen from its center and with the sight pointed right to the nadir.

Before explaining the method of drawing the picture, it may be remarked that the scene shown in Fig. 36, represents a view of the East river, in the vicinity of Blackwell's Island, as seen from the balcony of the third tower of the Queensboro Bridge; New York city is seen in the distance, then the East river, Blackwell's Island, the railing and the floor of the balcony, and Long Island City to the side of the balcony opposite from New York city. The visiograph is set so that the vertical central line of the fields is exactly coincident with the longitudinal central line of the bridge, which line becomes the diameter of the horizon. Beginning with the left eye, the artist observes all of that section of the scene within the lines a^{10} , a^{11} , a^{14} and a^{15} , which is an area 10 degrees longitudinally and 45 degrees latitudinally. This is sketched square by

square or piece by piece, without changing the set of the visiograph. As soon as this section is finished, the visiograph is turned to the left 20 degrees, so that by the use of 5 both vertical fields the section a^{11} , a^{16} and radially down to 45 degrees can be sketched. In this manner, the visiograph is adjusted step by step to enable the sketching of the scene section by section, from the horizon 10 down to 45 degrees level. The visiograph is now brought back to the starting point, and the sections of the vertical fields shown in Fig. 20 are substituted from those shown in Fig. 19. The visiograph is swung down 45 15 degrees so that some portion of the scene that has been already sketched and the nadir can be seen through the new fields. The scene is then completed by sketching it section by section as before. Before 20 sketching this lower belt of the scene, and in order to be sure of the coincidence of the degrees, the sight is directed down to the nadir, taking care of its being at right angles to the horizon, which is reflected 25 through the mirrors in front of the eyes according to the method of reflection shown in Fig. 25. It will be observed that in sketching a terrestrial cartograph, only two vertical adjustments of the visiograph is required, or in other words the scene is 30 sketched in two belts, both 45 degrees latitudinally.

When taking a celestial survey, three vertical adjustments of the visiograph are required, two adjustments by means of the 35 vertical fields. Fig. 19, a belt of 30 degrees is first sketched, then a belt of 15 degrees with the fields inverted and the vertical quadrants let down 15 degrees, and 40 finally by means of the vertical fields Fig. 20 a third adjustment for a belt of 45 degrees that reaches the zenith.

In drawing a spherical survey, or a combined terrestrial and celestial extended from 45 nadir to the horizon and from the horizon to the zenith, four vertical adjustments of the visiograph are necessary, first to the horizon which permits a belt of 30 degrees above and 45 below the horizon to be 50 sketched; second to the nadir; third to the 45 degree level above the horizon, and fourth to the zenith. The half semi-spherical celestial and terrestrial survey represented in Fig. 37 is also taken from the 55 Queensboro Bridge, New York city, and from the same spot as in Fig. 36. In the present cartographic view, the center of the picture is in the line of horizon which is a straight line coincident to the level of the cartographer's sight, as being the diameter of the semi-spherical cartograph of which only one half is represented here, showing part of the cartographer's right foot in its bottom or point of nadir. In this case the

visiograph is adjusted vertical four times 65 to sketch the belts lying between the points b^{10} and b^{11} , b^{11} and b^{12} , or nadir, b^{10} and b^{13} , and b^{13} and b^{14} or zenith. In sketching each belt, the visiograph is moved horizontally, step by step for the sketching of 70 the belts, section after section with the use of some arrangement of visual fields as in Fig. 36. The paper or plane of delineation on which the scene is sketched, is prepared previously with longitudinal, 75 latitudinal and diagonal lines, as a projection of the celestial sphere seen from its center when the sight is directed on a level with the horizon; to correspond with the lines of the fields. The transparent fields of the 80 visiograph may be used also for tracing the scene directly upon their inner surface.

From what has been said, it will be obvious that the visiograph must have a universal movement or movements on two axes 85 (vertical and horizontal) to be used for spherical surveys, but in taking panoramic views as in Fig. 35, only a rotatory movement about the vertical axis is necessary. In a panoramic view, the latitudinal and longitudinal lines are drawn straight and at right angles to each on the paper, as are the lines on the fields; but there in the fields, the longitudinal or horizontal lines become 90 arcs of circles parallel to the horizon and concentric to the eyes the moment they are seen with the visiograph, because of their 95 arcuate disposition, except the line of the horizon which is at a level with the sight. For this reason, the development of the 100 view upon the straight lines of the paper means, that the horizontals on the paper represent circles concentric to the horizon, and that the view represented to be seen correctly, must be turned in a cylindrical disposition and with the eye at the station 105 point or center of curvature.

The view shown in Fig. 35 covers 180 degrees of the horizon seen from the balcony of the third tower of Queensboro Bridge, 110 New York city; 0° in the middle of the picture passes over a gas tank at downtown, while 90° on either side runs along the middle of the bridge.

What I claim as new and desire to secure 115 by Letters Patent, is:

1. A visiograph comprising two parts of a vertical quadrant at right angle to two halves of a horizontal quadrant, both parts and both halves being divided into sections 120 of spherical degrees.

2. A visiograph comprising two vertical quadrants and two horizontal quadrants arranged at right angles to said vertical quadrants, visual fields representing projections 125 of the celestial sphere secured to said quadrants and adapted to be arranged concentric to the eyes of the user.

3. A visiograph comprising two quadrants, a spherical field provided with projections of the celestial sphere and secured to said quadrants, and adapted to be arranged concentric to the eyes of the user.

4. A visiograph comprising a pair of quadrants in the form of thin plates adapted to be presented edgewise to the respective eyes of the user, and means on each quadrant to divide a view into sections.

5. A visiograph comprising a pair of quadrants in the form of thin plates adapted to be presented edgewise to the respective eyes of the user, means on each quadrant to divide any view into sections horizontally, and means coöperating with the first means for dividing any view vertically into sections.

6. A visiograph comprising plate-like quadrants adapted to be held one in front of and edgewise to each eye, and means extending upwardly and downwardly from the quadrants to enable a view to be seen in vertical sections.

7. A visiograph comprising plate-like quadrants adapted to be held one in front of and edgewise to each eye, means extending upwardly and downwardly from the quadrants to enable a view to be seen in vertical sections, and means on each quadrant to enable a view to be seen in horizontal sections.

8. A visiograph comprising plate-like quadrants adapted to be held one in front of and edgewise to each eye, means extending upwardly and downwardly from the quadrants to enable a view to be seen in vertical sections, and means on each quadrant to enable a view to be seen in horizontal sections, said quadrants being adjustable toward or from each other for focusing the visiograph.

9. A visiograph comprising plate-like quadrants adapted to be held one in front of and edgewise to each eye, means for attaching the quadrants to the head of the user, and means on the quadrants for enabling any view to be measured in vertical and horizontal degrees.

10. A visiograph comprising plate-like quadrants adapted to be held one in front of and edgewise to each eye, means on the quadrants for enabling a view to be seen in sections, and means on the quadrants for preventing double sight.

11. A visiograph comprising plate-like quadrants adapted to be held one in front of and edgewise to each eye, means on the quadrant for enabling a view to be seen in sections, and means on the quadrants for preventing double sight, and sighting devices on the quadrants.

12. A visiograph comprising a structure adapted to be worn like spectacles, a pair of

means thereon for enabling a view to be seen in sections or to be measured vertically and horizontally, and means for preventing double sight.

13. A visiograph comprising a frame, means thereon for enabling a view of 90 degrees to be seen in sections, sighting devices on the frame disposed at right angles to the ray of vision, and reflecting means on the frame for enabling the sighting devices to be seen to ascertain the cardinal points in the horizon.

14. A visiograph comprising a frame, means thereon for enabling a view of 90 degrees to be seen in sections, sighting devices on the frame disposed at right angles to the ray of vision, and means on the frame for preventing double sight and enabling the sighting devices to be seen to ascertain the cardinal points in the horizon.

15. A visiograph comprising a frame made in adjustably connected parts, sighting devices on the said parts adapted to be brought into the convergence of a ray of vision of each eye, by the adjustment of the parts, sighting devices extending at right angles to the first mentioned sighting devices, and mirrors arranged to throw the image of the last mentioned sighting devices into the eyes.

16. A visiograph comprising two transparent fields divided into sections by intersecting lines, there being one field for each eye, and means for adjusting the fields toward each other to coincide at their inner lines with the line of vision.

17. A visiograph comprising two transparent fields divided into sections by degrees by intersecting lines, there being one field for each eye, means for adjusting the fields toward each other to coincide at their inner portions with the center of vision, and means disposed between eyes and fields to prevent double sight.

18. A visiograph comprising a pair of visual fields each having series of transacting lines dividing the field into sections for enabling a view to be seen in sections, one series of lines being converging, oppositely from the center of vision toward the horizon and the other series of lines being converging toward the zenith and nadir, and means for adjusting the fields toward or from each other whereby the inner edges of the fields meet in the center of vision.

19. A visiograph comprising a pair of lined visual fields having their inner lines lying in the rays of vision of the eyes of the user, each field having lines converging vertically from the horizon and lines transecting the converging lines to form sections of spherical degrees.

20. A visiograph comprising a pair of quadrants, one for each eye, a field frame

- on each quadrant, and a transparent sheet removably mounted on the field frame and having transecting lines dividing sheet into sections.
21. A visiograph comprising a pair of quadrants, one for each eye, a field frame on each quadrant, a transparent sheet removably mounted on the field frame and having transecting lines dividing sheet into 10 sections, a second field frame on each quadrant and extending transversely to the first frame, and a transparent sheet on the second frame and having transecting lines dividing the sheet into sections.
22. A visiograph comprising a support, a frame on the support, studs on the frame, and a spherical field having openings to receive the studs which retain the plate on the frame.
23. A visiograph comprising a field frame having a movable stretching member at one end and a fixed member at the other, and a field removably engaged with the said members.
24. A visiograph comprising a field frame having a hinged stretching member at one end, a lined transparent field removably attached to the frame and the stretching member, and a lock on the frame engageable 30 with the stretching member for holding the latter in stretching position.
25. A visiograph comprising a field frame including end members and top and bottom members, arms on one end member pivoted 35 to the top and bottom members, and movably supporting said end member, a transparent field detachably fastened to the members, seats on the top and bottom members to receive the movable end member to hold the 40 same in the position in which the field is held taut, and clips on the movable end member and engageable with the top and bottom members to hold the said end member in its seats.
26. A visiograph comprising a quadrant, a field frame, hooks on the quadrant and engageable with the frame, and clips on the frame engageable with the hooks.
27. A visiograph comprising a quadrant, 50 a field frame, hooks on the quadrant and engageable with the frame, clips on the frame engageable with the hooks, and a transparent field fastened detachably to the frame and having recesses to clear the hooks and 55 clips.
28. A visiograph comprising a quadrant, a field frame, hooks on the quadrant and engageable with the frame, clips on the frame engageable with the hooks, and 60 clamps for clamping the hooks in holding position.
29. A visiograph comprising quadrants for the respective eyes of the user, fields on the quadrants, means for adjusting the quadrants toward or from each other, and 65 clamps for holding the quadrants immovably in adjusted position.
30. A visiograph comprising field holding quadrants presented edgewise to the eyes of the user, means on the quadrants for resting on the nose, hinged ear engaging members on the quadrants, and an extensible element adjustably connected with the quadrants and extending around the back of the head of the user. 70
31. A visiograph comprising field holding quadrants presented edgewise to the eyes of the user, means on the quadrants for resting on the nose, hinged ear engaging members on the quadrants, an extensible element adjustably connected with the quadrants and extending around the back of the head of the user, and means for engaging the said element with the ends of the ear engaging members. 75
32. A visiograph comprising a supporting structure, vertically disposed quadrants spaced apart thereon, and fields on the quadrants for enabling a view to be seen in sections. 80
33. A visiograph comprising a supporting structure, vertically disposed quadrants adjustable thereon toward or from each other, and fields on the quadrants adapted to be arranged concentric with the eyes of the user. 85
34. A visiograph associated with three distinctive projections of the celestial sphere comprising a supporting structure, vertically disposed quadrants mounted thereon, field frames detachably mounted on the quadrants, and lined transparent fields mounted on the frames. 90
35. A visiograph comprising a supporting structure vertically disposed quadrants adjustable latitudinally on the structure, and fields carried by the quadrants. 95
36. A visiograph comprising a supporting structure, a pair of quadrants disposed vertically, fields thereon concentric with the eyes of the user, sighting devices on the quadrants, and mirrors on the structure by which sighting devices can be seen. 100
37. A visiograph comprising a supporting structure, fields disposed vertically thereon and concentric with the eyes of the user, sighting devices at the upper and lower extremities of the fields and disposed in lines meeting in the eyes and above and below the range of vision, and reflectors for bringing the sighting devices within the vision. 115
38. A visiograph comprising a supporting structure, fields disposed vertically thereon and concentric with the eyes of the user, sighting devices at the upper and lower extremities of the fields and disposed in lines meeting in the eyes and above and below the range of vision, reflectors for bringing the 120
- 125

sighting devices within the vision, sighting devices at the sides of the structure and out of the range of vision, and reflectors for bringing the latter sighting devices within the vision.

39. A visiograph comprising a supporting structure, fields carried thereby for enabling a view to be seen in sections, sighting devices on the upper portions of the fields and located beyond the range of vision, and a pair of reflectors located on the structure near and above each eye of the user for bringing the sighting devices within the vision.

40. A visiograph comprising a supporting structure, fields carried thereby for enabling a view to be seen in sections of degrees, sighting devices on the upper portions of the fields and located beyond the range of vision, a pair of reflectors located on the structure near and above each eye of the user for bringing the sighting devices within the vision, lateral sighting devices at the sides of the structure, and reflectors located on the structure between the lines of vision of the eyes for bringing the lateral sighting devices within the vision.

41. A visiograph comprising a supporting structure, fields thereon for enabling a view to be seen in sections, sighting devices disposed above and below and laterally of the range of vision, and reflectors for bringing the sighting devices within the vision.

42. A visiograph comprising vertical quadrants, a field on each quadrant for enabling a view to be seen in sections, sighting devices arranged on the lower ends of the quadrants and outside the range of vision, and reflectors mounted on the quadrants for bringing the sighting devices within the vision.

43. A visiograph comprising a thin plate-like structure presented edgewise to the eyes of the user, fields on and extending upwardly and downwardly from the structure for enabling a view to be seen in sections, and screens on the upper and lower sides of the structure for preventing double sight.

44. A visiograph comprising a thin plate-like structure presented edgewise to the eyes of the user, fields on and extending upwardly and downwardly from the structure for enabling any view to be seen in sections of spherical degrees, screens on the upper and lower sides of the structure for preventing double sight, sighting devices on the lateral portions of the structure and out of the range of vision and reflectors on the upper screens for bringing the sighting devices within the vision.

45. A visiograph comprising a thin plate-like structure presented edgewise to the eyes of the user, fields on and extending upwardly and downwardly from the structure for enabling a view to be seen in sections,

and screens on the upper and lower sides of the structure for preventing double sight, said screens each consisting of a fixed section secured to the said structure, and a movable section hinged to the fixed section.

46. A visiograph comprising a pair of quadrants symmetrically arranged and one for each eye, fields on the quadrants, means for adjusting the quadrants laterally toward and from each other, and clamps for holding the quadrants in adjusted position.

47. A visiograph comprising a pair of quadrants symmetrically arranged and one for each eye, fields on the quadrants, right and left screws for adjusting the quadrants laterally toward and from each other, and clamps for holding the quadrants in adjusted position.

48. A visiograph comprising a pair of horizontal symmetrically arranged quadrants and one for each eye, fields on the quadrants, means for adjusting the quadrants laterally toward or from each other, vertical quadrants on the horizontal quadrants, fields on the vertical quadrants, and means for adjusting the vertical quadrants laterally independent of the horizontal quadrants.

49. A visiograph comprising a pair of horizontal symmetrically arranged quadrants and one for each eye, fields on the quadrants, means for adjusting the quadrants laterally toward or from each other, vertical quadrants on the horizontal quadrants and extending above and below the latter, means at the upper and lower ends of the vertical quadrants for laterally adjusting them toward or from each other, and fields on the vertical quadrants.

50. A visiograph comprising a pair of horizontally disposed symmetrical quadrants adapted to be held one in front of each eye of the user, arcuate visual fields on the quadrants, vertically disposed quadrants, removably carried by the horizontal quadrants, and visual fields concentric with the eyes and arranged on the vertical quadrants and disposed in overlying relation with the inner portions of the first mentioned fields and projecting above and below the latter.

51. A visiograph associated with three distinctive projections of the celestial sphere for enabling the representation of partial, panoramic and spherical views, comprising symmetrical visual fields for the respective eyes of the user, said fields being curved and adapted to be arranged concentrically with the eyes both horizontally and vertically.

52. A visiograph for enabling the representation of partial, panoramic and spherical views, comprising symmetrical visual fields for the respective eyes, said fields being curved concentrically with the eyes both horizontally and vertically, and sighting de-

vices for enabling the visual axis of the visiograph to be directed successively at the four cardinal points in the horizon.

53. A visiograph for enabling the representation of partial, panoramic and spherical views by degrees longitudinally and latitudinally, comprising symmetrical visual fields for the respective eyes, said fields being curved concentrically with the eyes 10 both horizontally and vertically, and sighting devices for enabling the visual axis of the visiograph to be directed successively at the four cardinal points in the horizon, and means on the visiograph for focusing the 15 fields with respect to the zenith and nadir.
54. An instrument of the class described comprising a supporting structure, symmetrical fields having lines thereon for measurements and observation, and means for 20 adjusting the fields relatively to each other.

55. A visiograph for use in making partial, panoramic and spherical views, in combination with a pivotal movement and supporting structure on which the visiograph 25 turns on a vertical axis.

56. A visiograph of the class described, in combination of a pivotal movement and supporting structure including means for mounting the visiograph to turn on vertical 30 and horizontal axes.

57. A visiograph, in combination of a pivotal movement and supporting structure therefor of such size as to receive the user, said structure comprising a horizontal circular track, legs supporting the same, and a frame movably mounted on the track and carrying the visiograph.

58. A visiograph, in combination a pivotal movement and supporting structure 40 therefor of such size as to receive the user, said structure comprising a horizontal circular track, legs supporting the same, a movable frame on the track, and means for mounting the visiograph on the frame to 45 swing on a horizontal axis and to rotate with the frame.

59. A visiograph, in combination with a pivotal movement and supporting structure on which the visiograph is mounted to swing 50 horizontally and vertically on a common center located centrally of the eyes of the user.

60. A visiograph, in combination with a pivotal movement and supporting structure 55 therefor comprising a horizontal circular track of such radius as to accommodate the user's head between the track and visiograph, and a frame movable on the track about the center of curvature thereof and 60 to which frame the visiograph is fastened.

61. A visiograph, in combination with a pivotal movement and supporting structure therefor comprising a horizontal circular track of such radius as to accommodate the

user's head between the track and visiograph, and a frame movable on the track to turn on a vertical axis coincident with the center of curvature of the track, and means for pivotally mounting the visiograph on the frame to swing on a horizontal axis coincident with the center of curvature of the track.

62. A visiograph, in combination with a pivotal movement and supporting structure therefor comprising a horizontal circular track of such radius as to accommodate the user's head between the track and visiograph, and a frame having a base 70 slideable on the track and including an arch hinged on the base to swing on a horizontal axis, means for clamping the arch in different positions of adjustment, and means for adjustably mounting the visiograph on the arch.

63. A visiograph, in combination with a pivotal movement and supporting structure therefor comprising a horizontal circular track of such radius as to accommodate the user's head between the track and visiograph, and a frame having a base 85 slideable on the track and including an arch hinged on the base to swing on a horizontal axis, means for clamping the arch in different positions of adjustment, an arcuate member carried by the frame and disposed vertically, and means for clamping the visiograph to the arcuate member in different 95 positions thereon.

64. A visiograph comprising a pair of quadrants, one for each eye, a field frame 100 on each quadrant, a transparent sheet removably mounted on each field frame and having transecting lines dividing the sheet into sections, a pair of vertical quadrants, one for each eye, a vertical field frame on 105 each of the latter quadrants and extending upwardly and downwardly with respect to the first frames, and a transparent sheet on each of the second frames and having transecting lines dividing the sheet into sections. 110

65. A visiograph comprising two quadrants which are open directly in front of the eyes and each made of two parts, a structure adapted to be fitted to the head and to which the parts of the quadrants are 115 fastened, field frames on the quadrants, ruled transparent fields on the said frames, and bracing members arranged to connect the parts of each quadrant together at points adjacent the eyes and adapted to be 120 removed from in front of the eyes when the visiograph is used.

66. A visiograph, in combination with a pivotal movement and supporting structure therefor of such size as to receive the user, 125 said structure comprising a horizontal circular track, legs supporting the same, a movable frame on the track and consisting

of two hingedly connected semicircles disposed one vertically and the other horizontally, means for connecting the visiograph at three points to the frame, a bracket 5 mounted on one of the legs and extending upwardly to a point over the vertical semicircle and detachably pivotally connected with the latter, and means for holding a

zenith pointing needle on the upper portion of the said bracket.

In testimony whereof I affix my signature in presence of two witnesses.

SEBASTIAN CRUSET.
